UNITED STATES PATENT OFFICE.

WILSON W. PRIMM AND JEAN B. PRIMM, OF ST. LOUIS, MISSOURI, ASSIGNORS OF ONE-THIRD TO SARAH L. PRIMM, OF SAME PLACE.

BALANCED SLIDE-VALVE.

SPECIFICATION forming part of Letters Patent No. 361,647, dated April 19, 1887.

Application filed December 30, 1886. Serial No. 223,069. (No model.)

To all whom it may concern:

Be it known that we, WILSON W. PRIMM and JEAN B. PRIMM, citizens of the United States, residing at the city of St. Louis, State 5 of Missouri, have invented a certain new and useful Improvement in Balanced Slide-Valves for Steam-Engines, of which the following is a full, clear, and exact description.

Our invention relates to improved means of 10 balancing the slide-valves of locomotive and other steam engines, and it consists in the combination, with a slide-valve and its steam-chest and a balancing-piston connected with the slide-valve, of a pipe or passage communicating 15 with the piston-cylinder and with the atmosphere, a pipe or passage communicating with the steam-chest and with the atmosphere, and a three-way valve controlling both pipes or 20 passages, whereby steam may be admitted to the piston-cylinder and air to both cylinder and steam-chest at will.

It also consists in the combination, with a slide-valve and balancing-piston, of a port or passage leading from the exhaust-passage to 25 the cylinder of the balancing-piston and a loaded valve for counteracting the effect of varying back-pressure on the slide-valve.

It also consists in minor details of construction, which will hereinafter more fully appear.

On the accompanying drawings, Figure 1 is a longitudinal section of the slide-valve of a steam-engine fitted with our invention; Fig. 2, a transverse section of the same; Fig. 3, a 35 part plan thereof; and Fig. 4, a transverse section showing additional features of our invention as applied to locomotive slide-valves, or where varying back-pressure on the slide-valve has to be counteracted, like letters of 40 reference denoting like parts in all the figures.

Referring particularly to Figs. 1 to 3, *a* represents a slide-valve, and *b* the steam-chest, in the cover *c* of which is a cylinder, *d*, of suitable area, as hereinafter more particularly referred to, and opening at one end into the steam-chest *b*. In the cylinder *d* is fitted a piston, *e*, connected at its inner or under side, nearest the steam-chest *b*, to the top of the slide-valve *a* by a connecting-rod, *f*, the steam 45 from the steam-chest *b* pressing against the under side of the piston *e*, and thereby coun-

terbalancing the downward pressure on the slide-valve *a*.

As shown in Figs. 1 to 3, the rod or pin *g*, which couples the slide-valve *a* to the connecting-rod *f*, extends entirely across the top of the slide-valve *a* and has its bearings in four lugs, *h*, the bolts of which pass through the top of the slide-valve *a*, and are secured thereto by nuts screwed against packing-strips *i*, of 55 wrought-iron or other suitable material, interposed between the nuts and the under side of the slide-valve *a*, this arrangement being particularly intended for the application of our invention to existing slide-valves; but in 60 the case of new valves the lugs *h* may be cast on the slide-valve *a* without the necessity of the bolts, nuts, and packing-strips, as shown in Fig. 4.

The outer or upper end of the cylinder *d* is 70 closed by a cover, *j*, and communicates by means of a pipe, *k*, with branch 1 of a three-way cock, *l*, or other suitable regulating three-way valve, branch 2 of which is open to the atmosphere, and branch 3 communicating 75 with the steam-chest *b* by means of pipe *m*. The plug of the three-way cock *l* may be operated by the hand-wheel *n*, or by levers and rods, as found most suitable. The three-way cock *l* being adjusted so that branches 1 and 80 2 are in communication, and air thereby admitted from the atmosphere through pipe *k* into the cylinder *d* above the balancing-piston *e*, the engine is started, and as the slide-valve *a* reciprocates the balancing-piston *e* is also 85 reciprocated and adjusted to the varying positions of the slide-valve *a* by the connecting-rod *f*, any resistance to the movement of the piston *e* by the expansion or compression of the air on its other side being prevented by 90 the free inlet or exit of the air through the three-way cock *l* and pipe *k*.

An equilibrium is obtained between the steam-pressure on the balancing-piston *e* and the pressure of steam less the back-pressure 95 on the slide-valve *a* by observing the following formula: The area of the slide-valve in square inches multiplied by the pressure of steam per square inch, minus the area of the exhaust-space beneath the slide-valve multiplied by the back-pressure, is equal to the area of the balancing-piston *e*. When the 100

steam is shut-off from the steam-chest *b* and the slide-valve *a* is being moved by the momentum of the engine, air may be admitted to the steam-chest *b* by moving the three-way cock *l* so that branches 2 and 3 and pipe *m* are in communication.

In case of the lifting or displacement of the slide-valve *a*, steam may also be admitted from the steam-chest *b* to the cylinder *d*, above the balancing-piston *e*, by moving the three-way cock *l* so that branches 1 and 3 and pipes *k* and *m* are in communication, the effect of this being to return the slide-valve *a* to its proper position.

15 In the illustration of our invention shown in Fig. 4, which is specially adapted to a locomotive slide-valve, where the back-pressure on the slide-valve *a* is constantly varying, a valve, *o*, is fitted in the exhaust-passage *p* and loaded to a normal back-pressure by means of a spiral spring, *q*. The chamber of this valve *o* communicates with the space above the balancing-piston *e* by pipe *r*, so that when the back-pressure on the slide-valve *a* exceeds that 20 to which the valve *o* is loaded the valve *o* opens, and, admitting steam above the balancing-piston *e*, causes the pressure on the latter to counterbalance the excessive back-pressure on the slide-valve *a*. In this case the inflowing steam through pipe *r* to the space above the balancing-piston *e* is prevented from escaping through the three-way cock *l* into the atmosphere by a spring-valve, *s*, which is fitted at and closed over the mouth of branch 25 of the three-way cock *l* by the pressure of the steam until the balance of pressure on the slide-valve *a* is restored, when the valve *s* will

be opened by its spring, and free passage of air given through the three-way cock *l*, as before.

We claim as our invention—

40 1. The combination, with a slide-valve and a balancing-piston, of a port or passage leading from the exhaust to the cylinder of the balancing-piston, and a loaded valve, substantially as and for the purposes specified.

2. The combination, with a slide-valve and its balancing-piston, of the lugs *h*, provided with bolts, packing-strips *i*, rod or pin *g*, and connecting-rod *f*, substantially as and for the purposes specified.

45 3. In a steam-engine balancing slide-valve, the combination of balancing-piston *e*, connected with slide-valve *a* and working in cylinder *b*, a pipe or passage leading to the cylinder of the balancing-piston, a pipe or passage leading to the steam-chest, and three-way cock communicating with the atmosphere, substantially as shown, and for the purpose described.

50 4. In a steam-engine balancing slide-valve, the combination of balancing-piston *e*, connected with slide-valve *a* and working in cylinder *b*, valve *o*, pipes *r* *k*, three-way cock *l*, and spring-valve *s*, substantially as shown, and for the purpose described.

55 In testimony whereof we affix our signatures, in presence of two witnesses, this 13th day of December, 1886.

WILSON W. PRIMM.
JEAN B. PRIMM.
